UNITED STATES PATENT OFFICE.

DANNE PAMP, OF PHILADELPHIA, PENNSYLVANIA.

AUTOMATIC SWITCH-OPERATING DEVICE.

SPECIFICATION forming part of Letters Patent No. 773,974, dated November 1, 1904.

Application filed June 15, 1904. Serial No. 212,631. (No model.)

To all whom it may concern:

Be it known that I, DANNE PAMP, a subject of the King of Sweden and Norway, residing at Philadelphia, county of Philadelphia, and 5 State of Pennsylvania, have invented a certain new and useful Improvement in Automatic Switch-Operating Devices, of which the following is a specification.

My invention relates to a new and useful 10 improvement in automatic switch-operating devices, and has for its object to provide a device by which a switch may be opened or closed in advance of the car without necessitating the operator leaving the car.

15 With these ends in view this invention consists in the details of construction and combination of elements hereinafter set forth and then specifically designated by the claims.

In order that those skilled in the art to 20 which this invention appertains may understand how to make and use the same, the construction and operation will now be described in detail, referring to the accompanying drawings, forming a part of this specification, in 25 which—

Figure 1 is a plan view of the apparatus located between the car-rails; Fig. 2, a longitudinal section through a portion of a car and a portion of the road-bed, showing my apparatus in a position for operating the switch; 30 Fig. 3, a front elevation of the apparatus carried by the car and a cross-section through the apparatus located in the road-bed.

A represents the movable member of the 35 switch.

B is a guideway located in between the two tracks, and this guideway is provided with the two slots C, and pivoted below the guideway-plate B is the wedge-shape plate D, pivoted at the point D' to the guideway, and to the free end of the plate D is connected the 40 movable member A of the switch by means of the link E. When the switch is closed, one of the inclined sides of the plate D will cross one of the slots C, and when the switch is open the other side of the plate D will cross the other slot C. Therefore by passing a flat blade through one of the slots C which is crossed by the plate D said blade coming in 45 contact with the inclined side of the plate D

will move the plate D over, and thereby move the movable member A of the switch.

F is the flat blade utilized for operating the switch, and this blade is secured to a collar G, which collar is feathered upon the shaft H, 55 so that said collar may slide upon the shaft, but will be caused to rotate therewith.

I represents bearings depending from the platform of the car in which the shaft H is journaled.

The collar G is provided with an annular groove G', in which is adapted to rest a finger J, which finger is connected to a double-treadle foot-lever K, extending above the platform of the car. This lever K is pivoted 65 at the point K', and by pressing downward upon one of the treadles the collar G and blade F may be forced to the limit of their movement in one direction, and by pressing upon the other treadle they may be forced to the 70 limit of their movement in the opposite direction, so that the blade may be moved in a position above either one of the slots C.

L is a crank-arm secured to the shaft H, and this crank-arm is connected, by means of 75 a link M, to a foot-lever N, pivoted to the platform of the car.

O is a spring connected at one end to the crank-lever L and at the other end to the car, 80 normally holding the blade F horizontally.

When the foot-lever N is depressed, the shaft H will be rocked, forcing the blade F downward through one of the slots C, and by manipulating the lever K the blade F may be forced downward through any one of the slots 85 desired, thereby enabling the operator to move the plate in any direction desired, so as to open or close the switch, and as soon as the pressure of the foot is released from the lever N the blade F will resume its normal position. 90

Of course I do not wish to be limited to the exact construction here shown, as slight modifications could be made without departing from the spirit of my invention.

Having thus fully described my invention, 95 what I claim as new and useful is—

1. In an automatic switch-operating device, a guideway-plate secured in the road-bed between the rails, said guideway-plate provided with two longitudinal slots formed there- 100

through, a wedge-shape plate pivoted at its narrowest end to the under side of the guideway-plate, the free or larger end of the wedge-shape plate attached to the movable member 5 of the switch, one of the inclined sides of the wedge-shape plate adapted to always cross one of the slots through the guideway-plate, a flat blade carried by the car adapted to be forced downward through the slots for moving the wedge-shape plate to one side or the other, means for moving said blade laterally to allow the same to enter either one of the slots, means for rocking the blade downward, and a spring for returning the blade to its 15 normal position, as and for the purpose specified.

2. In an automatic switch-operating device, a guideway-plate located in the road-bed between the rails, said plate provided with longitudinal slots formed therethrough, a wedge-shape plate pivoted at its smaller end to the under side of the guideway-plate between the two slots, the larger end of the wedge-shape plate connected to the movable member of the 25 switch, one of the inclined sides of the wedge-shape plate adapted to cross the slot nearest the movable member of the switch when the switch is closed, the other side of the wedge-shape plate adapted to cross the other slot 30 when the switch is open, a flat blade carried by the car, a spring for normally holding said blade upward, means for forcing said blade downward to cause it to enter one or the other of the slots, means for shifting said blade

laterally to bring it above either one of the 35 slots, as and for the purpose specified.

3. In a device of the character described, the combination of railroad - rails, movable member of a switch and car with a guideway-plate located in the road-bed between the rails, 40 said guideway-plate provided with longitudinal slots formed therethrough, a wedge-shape plate pivoted at its smaller end underneath the guideway-plate between the two slots, a link connecting the larger end of the wedge-shape 45 plate with the movable switch member, one inclined side of the wedge-shape plate adapted to cross one slot when the switch is closed, and the other side adapted to cross the other slot when the switch is open, a transverse 50 shaft carried by the car and journaled in bearings depending therefrom, a flat blade slidably mounted upon said shaft but adapted to rotate therewith, a foot-lever carried by the car adapted to rock said shaft, a spring 55 for returning said shaft to its normal position, a double-treadle foot-lever carried by the car engaging the movable blade and adapted to slide the same in either direction to bring the blade above either of the slots in the guideway-plate, as and for the purpose specified. 60

In testimony whereof I have hereunto affixed my signature in the presence of two subscribing witnesses.

DANNE PAMP.
